(57) **CLAIM**

The ornamental design for a toss game target, as shown and described.

DESCRIPTION

FIG. 1 is a front perspective view of first embodiment thereof;

FIG. 2 is a rear perspective view of first embodiment thereof;

FIG. 3 is a front view of first embodiment thereof;

FIG. 4 is a rear view of first embodiment thereof;

FIG. 5 is a left side view of first embodiment thereof;

FIG. 6 is a right side view of first embodiment thereof;

FIG. 7 is a top view of first embodiment thereof;

FIG. 8 is a bottom view of first embodiment thereof;

FIG. 9 is a front perspective view of second embodiment thereof;

FIG. 10 is a rear perspective view of second embodiment thereof;

FIG. 11 is a front view of second embodiment thereof;

FIG. 12 is a rear view of second embodiment thereof;

FIG. 13 is a left side view of second embodiment thereof;

FIG. 14 is a right side view of second embodiment thereof;

FIG. 15 is a top view of second embodiment thereof; and,

FIG. 16 is a bottom view of second embodiment.
